UNITED STATES PATENT OFFICE.

THEODORE KLOS, OF WAUSAU, WISCONSIN.

AUTOMATIC DOOR.

1,163,760.

Specification of Letters Patent.

Patented Dec. 14, 1915.

Application filed May 26, 1915. Serial No. 30,585.

To all whom it may concern:

Be it known that I, THEODORE KLOS, a citizen of the United States, residing at Wausau, in the county of Marathon, State of Wisconsin, have invented certain new and useful Improvements in Automatic Doors; and I do hereby declare the following to be a full, clear, and exact description of the invention, such as will enable others skilled in the art to which it appertains to make and use the same.

This invention relates to doors, particularly to those of the sliding type, and has for its object the provision of a door which will be automatically opened by the weight of a vehicle approaching it.

An important object is the provision of an automatically opening door comprising two similar sections slidable toward and from each other, the movement of each being uniform and simultaneous with the movement of the other.

A further object is the provision of a door of this character which will automatically close when the vehicle has passed through.

An additional object is the provision of a door of this character which will be simple and inexpensive to manufacture, efficient and durable in service, not likely to get out of order, devoid of springs and levers, and a general improvement of the art.

With these and other objects and advantages in view, the invention consists in the novel construction and arrangement of parts to be hereinafter more fully described and claimed, and illustrated in the accompanying drawing, in which—

Figure 1 is a front elevation of the door and its operating mechanism showing it in its closed position, Fig. 2 is a side elevation, Fig. 3 is a cross sectional view on the line 3—3 of Fig. 1 showing the door and its associated parts in top plan, Fig. 4 is a horizontal sectional view on the line 4—4 of Fig. 1, Fig. 5 is a vertical sectional view, and Fig. 6 is a front elevation showing the door open.

Referring more particularly to the drawing the numeral 10 designates a wall which may be the front wall of a building and provided with an opening 11 adapted to be closed by a pair of doors 12 provided with hangers 13 carrying rollers 14 disposed upon

a track 15 supported as at 16 upon the wall 10. The lower ends of the doors 12 are prevented from swinging movement by strips or cleats 17.

My invention consists in the provision of means automatically operated by a vehicle approaching the doors to open the doors. To this end I provide a platform 18 of a width substantially that of the opening 11. The platform 18 is hinged as shown at 19 upon the floor 20 and has its other end adapted to lie adjacent the doors when the platform is lying flat.

In order that the depression of the platform 18 caused by the driving of a vehicle thereonto may be utilized for opening the doors I provide brackets 21 secured upon the wall 10 and having journaled thereon pairs of pulleys 22 and 23. Upon each side of the platform 18 adjacent its free end is secured a flexible member 24 which may conveniently be a cable. The members 24 extend upwardly and are trained about the inner pulleys 22 after which their free ends are connected with the farther edge of each adjacent door 12 as shown at 25.

It will be seen that when a vehicle is driven onto the platform 18, the flexible members 24 will be pulled downwardly, thereby separating the doors and allowing the vehicle to pass through.

In order to provide means whereby the doors will automatically close when the vehicle has passed through I provide a bracket 26 at each side of the door opening and at a considerable distance therefrom, secured upon the wall 10. These brackets 26 each support the upper ends of a pair of vertical rods 27 extending upwardly from the cleats 17. Upon each pair of rods 27 is slidably mounted a weight 28 having lugs 29 embracing the rods 27. Each weight 28 is formed preferably of a plurality of disks 30 secured together by a bolt 31 whereby more or less disks may be used for varying the weight. Each weight 28 has secured thereto a flexible member 32 which is trained about the adjacent outer pulley 23 and which has its free end connected with the nearer edge of the farther door 12. When the doors are opened as previously described, the weights 28 will be lifted and when a vehicle has passed through the door-way and passed en-

tirely off from the platform 18, the weights will slide down upon the rods 27 and will consequently draw the doors together.

Having thus described my invention, I claim:

The combination with a door-way and a pair of sliding doors therefor, of a platform having one end adjacent said doors and its other end hinged, a bracket secured at each 10 side of said door-way, a pair of pulleys journaled on each bracket, flexible members connected with the sides of said platform adjacent its free end, trained about corresponding ones of said pairs of pulleys and

connected with the farther edge of each 15 nearer door, vertically disposed guides adjacent the sides of the door-way, a weight 20 slidable upon each guide, and a flexible member connected with each weight, trained about the other of each pair of pulleys and connected with the nearer edge of the farther door.

In testimony whereof, I affix my signature, in the presence of two witnesses.

THEODORE KLOS.
